UNITED STATES PATENT OFFICE.

EMILE GÉRARD, OF LIMOGES, FRANCE.

DESIGN FOR A COVERED DISH.

SPECIFICATION forming part of Design No. 24,793, dated October 29, 1895.

Application filed September 9, 1895. Serial No. 562,000. Term of patent 7 years.

To all whom it may concern:

Be it known that I, EMILE GÉRARD, a citizen of the French Republic, residing at Limoges, France, have invented and produced a new and original Design for Dishes, of which the following is a full, clear, and exact description, reference being had to the accompanying drawings, in which—

Figure 1 is a top view illustrating a dish 10 embodying my design, and Fig. 2 is a side elevation of the same.

The principal features of my design are the configuration of the leaf-like portions extending inwardly from the rim of the cover, with 15 plain portions interposed between the said leaf-like portions along the rim of the cover, and the general contour of the dish itself.

In the drawings, A represents the body of the dish proper, which has leaf-like ornaments 20 α extending upwardly from the plain

base throughout the circumference thereof, and has ornamental handles b extending from each side. The contour of this dish in horizontal section is circular and is provided with an outwardly-extending bilge c . The cover B 25 follows the general contour of the top of the body portion of the dish and has leaf-like portions d extending inwardly from the rim thereof at intervals around the entire extent, leaving plain unornamented portions interposed between the same, and has a central leaf-like star e , from which projects an ornamental handle f .

What I claim is—

The design for a dish, substantially as 25 herein shown and described.

EMILE GÉRARD.
